ROTARY VALVE AND INTERNAL COMBUSTION ENGINE CONSTRUCTION AND LUBRICATION

Aulden D. Snyder, Cleveland, Ohio, assignor of one-third to William J. Wesseler, Cleveland, Ohio

Application June 13, 1935, Serial No. 26,429

3 Claims. (Cl. 123—59)

This invention, as indicated, relates to an improvement in Internal combustion engine and valve construction set forth in United States Patent No. 1,883,038 dated October 18, 1932. More particularly it relates to an improvement in rotary valve and internal combustion engine construction and lubrication. One of the principal objects of my invention is to eliminate thru the utilization of the lubricating medium as a cooling medium, the causes for objections and failures usually associated with rotary or articulated valve mechanisms, namely: warping, sticking, improper or uncontrolled lubrication, hotspotting and preignition at high operative engine speeds.

Another object of my invention is to provide a booster pump as an inherent function of the rotary valve mechanism, to serve as the means for supplying lubrication to the operative parts of an internal combustion engine, in combination with a suction and pressure pump.

Another object of my invention is to provide a means for control of and positive removal of surplus or unwanted lubrication from certain portions of a rotary valve mechanism.

A further object of my invention is to provide a method of removal of surplus heat accumulated by the lubricating oil used for both lubrication and cooling.

While the accompanying drawing serves to illustrate certain mechanism embodying my invention, such disclosed means constitutes but one of the various mechanical forms in which the principle of my invention may be used. In said annexed drawing:

Figure 1 is a front elevation of an internal combustion engine embodying the principles of my invention; Figure 2 is a vertical section thru the upper portion of the engine taken along the line 2—2 shown in Figure 4; Figure 3 is a plan view of the valve mechanism as it appears with the upper portion of the sectional cylinder head removed; Figure 4 is a plan view of the lower portion of the sectional cylinder head as it appears after removal of the upper cylinder head portion, filler portion and valves.

Similar numerals are used to refer to similar or the same parts thruout the various views.

Referring to Figure 1 of said annexed drawing, the cylinder block and crankcase 1 is provided with an oil reservoir 2, a sectional cylinder head comprised of upper portion 3, filler portion 4, and lower portion 5. A suction and pressure oil feed pump 6 draws oil from reservoir 2 thru suction line 7, and feeds oil under pressure thru oil pressure line 8 to the valve mechanism. Any surplus

lubricant supplied to the valve mechanism is returned thru surplus oil suction line 9 leading to suction side of said suction and pressure pump 6. A valve booster lubricant discharge line 10 carries lubricant under pressure created by the said valve mechanism to oil cooler and distributor 11. Oil feeds from said distributor and cooler thru distribution tube 12 to main crankshaft bearings 13. After lubrication of operative parts of engine within the crankcase and cylinder blocks, the oil drops back into reservoir 2 where it accumulates and the cycle of flow is thus made complete and continuous.

A housing 14 at the forward end of the crankshaft contains spiral bevel gears which serve to drive the valve and ignition drive shaft 15. A carburetor 16 is mounted on upper portion 3 of said cylinder head, and connects directly with an intake manifold contained in said upper portion of the sectional cylinder head. Likewise, an exhaust pipe 17 is mounted on side of said upper cylinder head portion and connects directly with an exhaust manifold within said head section.

In Figure 2 of said annexed drawing, the lower cylinder head section 5 is bolted to jacketed block 1. Within said lower head section is combustion chamber 18, valve intake port 19, valve lubrication passageway 20, fed by oil pressure line 8. Said cylinder head section contains counterbored holes for anchoring drilled pivot pins 21. Oil pressure passageway 20 connects with longitudinal oil distributing passageway 22. Said distributing passageway feeds lubricant thru coincident transverse drilled holes in said drilled pivot pins 21, and then thru drilled pivot pin passageway 23 in said pivot pins. On upper surface of lower head portion 5, is oil ring groove 24, and oil surplus removal grooves 25. Said surplus removal grooves connect thru drilled holes to longitudinal oil suction passageways 26, 26, and thus constantly remove any surplus lubricant from the vicinity of the valve ports. A spark plug 27 for ignition of gases within said cylinder, is mounted in wall of intake port 19. Cored cooling jackets 28 remove heat from lower cylinder head section 5.

Mounted on lower head section 5 is filler piece section 4, of thickness equal to the thickness of rotary valve disc 29 plus running or oil film clearance. Hollow valve disc 29 is mounted on hollow pivot pin 21. Oil under pressure is fed thru line 8, into passageway 20, and thence to distributing passageway 22, thru drilled pivot pin passageways 23, thru transverse drilled holes 30 in said pivot pin walls, into undercut oil ring 31, thence

thru drilled holes 32 in disc valve hub, into interior 33 of hollow disc gear valve 29. Contact of oil fed under pressure, with the interior wall surfaces of said hollow rotary disc gear valves, and with the walls of the disc valve port 34, serves as a moving surface contact cooling medium. Oil within said disc valve then flows under pressure thru drilled passageways 35 and 36, to oil film clearance space between hollow 10 valve disc plane surfaces and adjoining sectional head surfaces. Part of the oil fed through drilled passageways 23 in said pivot pins and into holes 30 and undercut oil ring 31, flows between pivot pin bearing surface and hub bearing surface 15 of said valve disc for lubrication, and reaches oil ring groove 24 on upper surface of lower head section 5, as well as annular oil groove 37 on upper surface of said valve disc. Said annular oil groove 37 also receives part of its oil supply directly thru drilled passageway 23 in said pivot 20 pin, and said supply serves as an auxiliary feed to upper surface of valve disc 29, said surface receiving the higher unit bearing pressure of the two wiping surfaces of the hollow disc valve. Oil 25 circulation as described is indicated by directional arrows. Completing the valve mechanism chamber is upper cylinder head section 3, with plane lower surface receiving the pressure and thrust of the articulated disc gear valves 29. Within 30 said upper cylinder head section is intake manifold 38, exhaust gas manifold 39, and circulation cooling jacket 40. Directly connected to intake manifold 38, is carburetor downdraft connection 16. Directly connected to exhaust gas manifold 39 is exhaust pipe 17.

It is obvious that where jacket cooling is shown on the attached drawing, air cooling fins or other external cooling means could be substituted.

In Figure 3 of the annexed drawing, the upper 40 portion of valve drive shaft 15 is keyed to valve driving pinion 41, which meshes with the first articulated hollow disc gear valve 29. Directions of rotation of said driving pinion and disc gear valves are as indicated by the arrows. Oil under 45 pressure feeds thru oil pressure line 8, thru oil lead 20, into oil distributing passageway 22, thence thru passageways 23 in pivot pins 21.

Part of said pressure fed oil flows into upper 50 annular oil groove 24 on upper surface of valve disc 29, and another part flows into the interior 33 of said hollow disc gear valves. Oil reaching 55 said valve interior flows out thru drilled holes 35 and 36 to running clearance space between surfaces of said valves and containing adjacent 60 surfaces of upper and lower head sections, thus affording adequate lubrication of the wiping surfaces of said disc gear valves. The film of oil on 65 said wiping surfaces is thrown to the peripheries of said disc gear valves by centrifugal action. At 70 the peripheries of respective valves the oil is picked up by the gear teeth, in the restricted space between said teeth and the conforming surface of the filler section 4. The gear teeth of 75 said disc gear valves thus act in the capacity of a booster pump. Where direction of disc gear rotation is contrary to the desired direction of lubricant flow, the filler portion 4 is designed to afford excessive clearance space between its inner 80 surface contour and the addendum circle of said gear teeth. Where direction of rotation is in same direction as desired lubricant flow, the filler piece inner contour conforms closely to the addendum circle of the respective disc gear teeth. Thus, by referring to Figure 3 of the drawing, it 85 will be noted that all oil which has passed to the

peripheries of respective disc gear valves by virtue of centrifugal action or otherwise, is brought to booster discharge opening 42 by the booster pump action of the articulated valve mechanism. Oil which reaches said discharge opening 42, is carried into valve booster oil discharge line 10, connected to said opening 42 in lower head section 5.

In Figure 4 of said annexed drawing, surplus lubricant is prevented from gaining access to intake ports 19, and exhaust ports 43, by oil surplus 10 collection grooves 44, in the vicinity of the leading edges of said ports. Oil so collected is removed thru suction openings 45, interconnecting said oil collection grooves and longitudinal oil 15 surplus suction passageways 26, 26. The surplus lubricant then continues to flow thru connecting passageway 46, interconnecting the two longitudinal passageways 26, 26, and connecting to surplus oil removal suction line 9.

On the upper plane surface of lower head section 5, and on the lower plane surface of upper head section 3, are radial oil grooves 47, one on each surface for each hollow disc gear valve. These radial grooves are fed by annular grooves 24 in lower head section 5, and by annular oil 25 grooves 37 on upper surfaces of respective disc gear valves.

It will be observed that in the manner described the hollow disc gear valves are operated 30 between cooling jacketed surfaces, and the ports in the head sections are completely cooling jacketed. The hollow disc gear valves have a continual supply of flowing oil thru them. Thus, the oil serves as both a lubricating and cooling medium, and the port in respective valve discs is 35 oil jacketed. The flow of the lubricant thru the hollow disc gear valves assists materially in the removal of heat. The adjacent cooling jackets assist in removal of heat from the lubricating medium, and the lubricant cooler and distributor 40 41 removes any undesirable residual heat from the oil before it is fed by the booster pump action of the valve mechanism to the interior working parts of the engine. The walls of the disc valve port 34 are subjected alternately to intake and 45 exhaust gas temperatures, and further cooled by the temperature gradient between said walls and the surrounding flow of lubricant under pressure. The lubricant is in turn cooled by the ambient flow in the cooling jacketed head sections of the 50 engine. Such cooling prevents the lubricant from attaining a temperature conducive to sludging, and further prevents warping, sticking, hotspotting or preignition on the part of the valves. Lubricant is supplied to the valve mechanism as 55 fast as it is dissipated or required, consistent with proper lubrication, and any surplus lubricant is removed from regions where it is unwanted, by positive suction means.

The described construction is conducive to 60 maximum volumetric efficiency thru its favorable effect on variable factors that determine volumetric efficiency, namely: frictional resistance encountered in passage of gas from carburetor into cylinder; the gas velocity; the amount of heat received by the charge while passing into cylinder; and timing of the intake and exhaust.

From the foregoing description it will be understood that heat picked up by the lubricant used for both lubrication and cooling of the 70 rotary valves, is removed by the action of the cooler, before the lubricant is fed to the inner working parts of the internal combustion engine. This arrangement is also conducive to a more uniform temperature of the lubricating medium, since the 75

circulation of the engine cooling medium will serve to add heat to cold oil in cold weather operation, and to remove heat from hot oil in hot weather operation.

5 It might also be pointed out that the trailing edges of the ports 19 and 43 in the lower section 5 of the cylinder head shown in Figure 4, may be provided with a suitable abrasion resisting material such as Stellite to provide a longer life for 10 the scraping edges of the ports for removal of any soot or carbon deposit from the wiping surfaces of the respective valve discs. Also, the hollow disc gear valves are adaptable to cast or forged construction. In the latter case, the forged sections 15 would be welded together before machining. In the case of cast valves the interior would be cored and the gear teeth would be made as a part of a ring gear which would be shrunk on and keyed.

Other modes of applying the principle of my 20 invention may be employed instead of the one explained, change being made as regards the mechanism herein disclosed, providing the means stated by any of the following claims or the equivalent of such stated means be employed.

25 I therefore particularly point out and distinctly claim as my invention:

1. An apparatus of the character described, having in combination a cylinder block, a head provided on the upper side thereof, inlet and exhaust passageways formed through said head, cooling chambers surrounding said passageways, a plurality of hollow intermeshing gear disc rotatable valves flat on each face and mounted on pins within said head, intake passageways for oil 30 through said pins into the interior of said discs, oil discharge ports through the upper and lower surfaces of said discs, said ports being positioned to travel paths spaced from the inlet and exhaust passageways, oil return ports adjacent said passageways inwardly of the paths of travel of said oil discharge ports, a pump, and oil lines connecting said respective intake passageways and oil return ports directly with said pump.

2. An apparatus of the character described,

having in combination a cylinder block, a head provided on the upper side thereof, inlet and exhaust passageways formed through said head, cooling chambers surrounding said passageways, a plurality of hollow intermeshing gear disc rotatable valves flat on each face and mounted on pins within said head intake, passageways for oil through said pins into the interior of said discs, oil discharge ports through the upper and lower surfaces of said discs, said ports being positioned to travel paths spaced from the inlet and exhaust passageways, oil return ports adjacent said passageways inwardly of the paths of travel of said oil discharge ports, a pump, an oil reservoir adjacent said pump, oil lines connecting said respective intake passageways and oil return ports directly with said pump, and an auxiliary oil line 15 communicating with the head adjacent the lateral margins of said discs to return oil to said reservoir.

3. An apparatus of the character described, having in combination a cylinder block, a head provided on the upper side thereof, inlet and exhaust passageways formed through said head, cooling chambers surrounding said passageways, a plurality of hollow intermeshing gear disc rotatable valves flat on each face and mounted on pins within said head intake, passageways for oil through said pins into the interior of said discs, oil discharge ports through the upper and lower surfaces of said discs, said ports being positioned to travel paths spaced from the inlet and exhaust passageways, oil return ports adjacent said passageways inwardly of the paths of travel of said oil discharge ports, a pump, an oil reservoir adjacent said pump, oil lines connecting said respective intake passageways and oil return ports directly with said pump, and oil cooling and engine lubrication passageways connected with an auxiliary oil line communicating with the head 40 adjacent the lateral margins of said discs to return oil to said reservoir.
